(57) **CLAIM**

The ornamental design for a ground anchor, as shown and described.

DESCRIPTION

FIG. 1 is a perspective view of a ground anchor according to the design of my invention, the phantom lines depicting a preferred environment;

FIG. 2 is an enlarged top plan view thereof;

FIG. 3 is a side elevational view thereof; and,

FIG. 4 is a bottom plan view thereof.

The phantom lines are for environmental purposes only and form no part of this invention.
